(57) **CLAIM**

The ornamental design for smart swimming goggles, as shown and described.

DESCRIPTION

FIG. 1 is a perspective view of smart swimming goggles showing our new design.

FIG. 2 is a perspective view of the smart swimming goggles from an oblique rear angle.

FIG. 3 is a front view of the smart swimming goggles.

FIG. 4 is a rear view of the smart swimming goggles.

FIG. 5 is a left side view of the smart swimming goggles.

FIG. 6 is a right side view of the smart swimming goggles.

FIG. 7 is a top view of the smart swimming goggles.

FIG. 8 is a bottom view of the smart swimming goggles; and,

FIG. 9 is an enlarged view of the selected portion in FIG. 2. The evenly dashed broken lines shown in the drawings depict portions of the article and form no part of the claimed design. The unevenly dashed broken lines in FIGS. 2 and 9 demarcate the boundaries of the enlarged view and form no part of the claimed design.
